CIRCUIT CONTROLLER

Robert A. Woods, Penn Township, Allegheny County, and William E. Smith, Edgewood, Pa., assignors to The Union Switch & Signal Company, Swissvale, Pa., a corporation of Pennsylvania

Application May 29, 1943, Serial No. 488,978

10 Claims. (Cl. 200—5)

Our invention relates to circuit controllers, and particularly to circuit controllers for assembly on a control panel as one of a compact group of similar units for controlling railway switches and signals or other apparatus.

One object of our invention is to provide a circuit controller equipped with safety contacts, that is, contacts which are positively moved to both their open and closed positions by cam action and which do not rely on spring pressure to position the movable contact fingers in either the open or closed positions of the contacts.

Another object of our invention is to provide a circuit controller having the contacts grouped and assembled in a manner which will enable the controller to withstand a 3000 volt ground test and still keep the overall size of the controller to a minimum so that it can be used in the limited space available on the control panels of centralized traffic control systems.

Another object of our invention is to provide a circuit controller having two groups of contacts operated by a single cam in such manner that the operation of the contacts of the one group will be completed before the operation of the contacts of the other group is initiated.

Another object of our invention is to provide a controller in which the contacts of each group are operated through the medium of a contact shifter clamped at one end in the contact stack and provided at the other end with an insulating contact operating member and with a cam follower secured to said member and cooperating with the controller cam to provide the sequential operation of the contacts referred to in the preceding paragraph.

A further object of our invention is to provide a controller in which the number of contacts which are provided can be readily varied.

A still further object of our invention is to provide a controller which necessitates a more positive act on the part of the operator to initiate its operation than has heretofore been customary.

According to our invention, the controller comprises an L-shaped supporting bracket the short leg of which is adapted to be secured to the rear side of a suitable control panel and the long leg of which extends rearwardly away from the panel and is provided at its rear end with a stack of contacts comprising cooperating fixed and movable contact fingers clamped between superposed blocks of insulating material. The contacts of the stack are disposed in units of four contacts each arranged in a horizontal row,

and the units are so constructed that as many units as desired may be assembled one above the other. The contacts of each unit are divided into groups of two or more contacts each, and each group is operated by a contact shifter comprising a flat spring clamped at one end in the contact stack, and provided at the other end with a return bend to increase the stiffness in the horizontal plane without interfering with the necessary flexing in the vertical plane. An insulating contact operating member provided with slots which receive with some clearance the free ends of the movable contact fingers of the associated group of contacts is clamped between a vertical surface formed by the return bend and a bracket which carries a forwardly projecting cam follower. The cam followers extend into and cooperate with a cam slot formed in a cam secured to an operating shaft journaled in suitable supporting bearings. The shaft extends forwardly through the panel and carries an operating knob. The shaft is rotatable between two extreme positions, and the cam is so designed that when the shaft is rotated from one extreme position to the other, the one cam follower will remain stationary during one-half of the stroke of the operating shaft and the other follower will remain stationary during the other half of the stroke, whereby a sequential operation of the two groups of contacts is obtained. The controller also includes suitable detent means to cause the operating shaft to complete its stroke in either direction with a snap action, as well as latch means which must be operated before the operating knob can be moved away from either extreme position.

Other objects and characteristic features of our invention will become apparent as the description proceeds.

40 We shall describe two forms of circuit controllers embodying our invention, and shall then point out the novel features thereof in claims.

In the accompanying drawings, Figs. 1, 2, 3 and 4 are top plan, side elevational, left-hand and right-hand end views, respectively, showing one form of circuit controller embodying our invention. Figs. 5 and 6 are sectional views taken on the lines V—V and VI—VI, respectively, of Fig. 2. Figs. 7, 8 and 9 are top plan, side and front views respectively showing another form of circuit controller embodying our invention. Figs. 10 and 11 are sectional views taken on the lines X—X and XI—XI respectively of Fig. 8.

Similar reference characters refer to similar parts in each of the several views.

Referring first to Figs. 1 to 4, inclusive, the circuit controller here shown comprises an L-shaped supporting bracket 1 provided with a relatively short vertical leg 1a and a relatively long horizontal leg 1b. The vertical leg 1a is adapted to be secured to the rear face of a control panel indicated at 2 in the drawings, and for this purpose it is provided with two laterally spaced tapped holes 3 which receive machine screws 4 extending through countersunk holes 5 provided in the panel.

An operating shaft 6 is journaled in spaced bearing openings 7 and 8 provided respectively in the vertical leg 1a of the bracket 1 and in a bearing bracket 9 secured to the horizontal leg 1b of the bracket 1, and this shaft extends outwardly through the panel 2 and is provided at its outer end with an operating knob 10 by means of which the operating shaft may be rotated between two extreme positions. The extreme positions of the shaft are determined by detent means comprising a cam 11 (see Fig. 5) pinned to the shaft 6 adjacent the rear side of the vertical portion 1b of the bracket 1, and cooperating with a steel ball 12. The steel ball 12 is disposed with some clearance within aligned vertical openings 13, 14 and 15 formed respectively in the lower part of the bearing bracket 9, in a spacing member 16 disposed between the bracket 9 and the leg 1b of the bracket 1, and in the leg 1b, and is constantly pressed into engagement with the cam 11 by means of a button 17 secured to one end of a biasing spring 18, the other end of which is secured to the underside of the leg 1b. The cam 11 is formed with curved shoulders 11a and 11b which cooperate with the ball 12 to limit the movement of the shaft, and with an eccentric intermediate portion 11c of varying radius so shaped that as the shaft approaches the position in which either shoulder engages the ball 12, the force of the biasing spring acting through the ball and cam surface will exert a torque on the shaft which acts to cause the shaft to complete its stroke with a snap action. The stroke of the shaft may be varied as conditions require, but with the parts constructed as shown in the drawings this stroke is 180°.

The cam 11, in addition to serving as a means to limit the stroke of the shaft 6 and to cause the shaft to complete its stroke with a snap action also cooperates with latch means for latching the shaft in its two extreme positions. This latch means as here illustrated comprises a latch spring in the form of a flat metal strip 20 provided at one end with a U-shaped return bend 20a and at the other end with an offset portion 20b. The strip 20 is secured to the bearing bracket 9 by means of screws 21 passing through the short leg of the return bend 20a, and extends transversely across the controller directly in back of the cam 11 and cooperates at the offset portion 20b with a push button 22 slidably mounted in a bushing 23 extending through and secured to the panel 2. A pin 24 is secured to the latch spring intermediate its ends, and this pin cooperates with two diametrically opposite holes 25 and 26 formed in the cam in such positions that the hole 25 will align with the pin when and only when the shaft occupies its one extreme position and the hole 26 will align with the pin when and only when the shaft occupies its other extreme position. The latch spring is biased by its own resiliency to the position in which the pin 24 will enter whichever one of the holes 25 and 26 is in alignment with it, and it will be seen therefore that

the pin can be withdrawn from such hole by pushing inwardly on the push button 22. It will be obvious, of course, that when the pin 24 is within either one of the holes 25 and 26 it will lock the shaft against rotation, and it follows therefore that in order to rotate the shaft away from either extreme position it is necessary to operate the push button. The parts are preferably so spaced that an operator wishing to move the shaft from either extreme position to the other will have to press the push button with one hand and simultaneously rotate the shaft with the other hand.

The contacts of the controller are arranged in a stack mounted on the rear end of the horizontal leg 1b of the supporting bracket 1, and are operated by a cam 45 secured to the rear end of the operating shaft in a manner which will now be made clear.

The contact stack as shown comprises four contacts, each consisting of a fixed contact finger 30 and an associated movable contact finger 31 clamped adjacent their rear ends between superposed blocks 32, 33 and 34 of insulating material. The insulating blocks are secured to the horizontal leg 1b of the bracket 1 by means of screws 35 disposed between the outer and inner contacts, and the middle block 33 is formed in its upper and lower edges with notches 33a and grooves 33b which receive tongues 32a and 34a formed on the upper and lower blocks 32 and 34, respectively. The fixed and movable fingers are disposed in the notches or grooves as the case may be, and it will be obvious, therefore, that the notches and grooves serve to maintain the fixed and movable contact fingers in the proper parallel spaced relation.

The contact fingers may be assembled to form either normally closed or normally open contacts merely by reversing the positions of the fixed and movable contact fingers. As illustrated, the two contacts at one side of the stack are assembled one way and the remaining two contacts are assembled the other way. Associated with each fixed contact finger is a relatively stiff metal stop 39 which is clamped between the same two insulating blocks as the associated fixed finger either above or below the finger depending upon whether the contact is arranged as a normally open or a normally closed contact, and which stop cooperates with the associated finger to position it when it is not engaged by the associated movable contact finger.

The normally open contacts comprise one group of contacts, and the normally closed contacts another group, and the contacts of each group have associated therewith a contact shifter comprising a flat spring 40, an insulating contact operating member 41, and a cam follower 42. The flat springs 40 are disposed above the contact fingers of the associated group of contacts in parallel spaced relation, and are clamped at their rear ends between the upper insulating block 32 and a pressure plate 52 through which the screws 35 pass. The forward ends of the springs are each formed with a return bend 40a which increases the stiffness of the spring in the horizontal plane without interfering with its ability to flex in the vertical plane. Each return bend is shaped to present a vertical surface 40b to which an associated one of the contact operating members 41 is secured as by riveting. Formed in each contact operating member 41 are slots 41a which receive the forward ends of the movable contact fingers with clearance to thereby

operatively connect the fingers with the contact operating members.

It should be pointed out that with the contact stack constructed in the manner just described, the screws 35 which clamp the various parts of the stack together are disposed as far from the fingers as possible, and are adequately insulated from the fingers. This fact together with the arrangement of notches, grooves, and tongues which hold the fingers in alignment enables the controller to be made as compact as possible and still be able to withstand a 3000 volt breakdown test.

Each cam follower 42 is mounted on a support 43 secured to the horizontal surface 40b of the associated spring 40 at the outer side of the associated contact operating member, and the two cam followers extend into and cooperate with a cam slot 44 (see Fig. 6) formed in the previously referred to cam 45. The cam follower support associated with the normally open contacts is turned in the opposite direction from the one associated with the normally closed contact, that is to say, the one extends upwardly and the other downwardly, and the parts are so proportioned that with the supports disposed in this manner, the cam followers will be on diametrically opposite sides of the axis about which the cam rotates. The cam slot is formed with a portion which is concentric with respect to the shaft 6 and a portion which is eccentric with respect to the shaft, and the parts are further so proportioned that when the shaft is in its normal extreme position in which it is shown in the drawings, the upper follower will be in the eccentric portion and the lower cam follower will be in the concentric portion. The parts are still further so proportioned that when the shaft is rotated from the extreme position shown to its opposite extreme position, the upper follower will remain in the part of the cam slot 44 which is eccentric with respect to the axis of the shaft until the shaft reaches its mid stroke position and will then enter the concentric portion of the slot, whereas the lower cam follower will remain in the concentric portion of the slot until the shaft reaches its mid stroke position and will then enter the eccentric portion of the slot.

To indicate the position of the operating knob 10 the knob is provided with an arrow 10a. This arrow also serves under certain conditions as a means for indicating the direction of a traffic route set up by operation of the controller. Moreover, the knob has attached thereto a semicircular shutter 10b which for certain installations of the controller serves to obscure in one extreme position of the controller a legend provided on the panel, and to expose the legend in the opposite extreme position. The legend is intended to serve as a reminder to the operator of the condition of the device controlled by the controller, and as shown comprises the two words "Hold East."

The operation of the controller as a whole is as follows: When the controller shaft occupies its normal extreme position in which it is shown in the drawings, and it is desired to reverse the controller, the operator will first press the push button 22 to unlock the operating shaft, and will then rotate the shaft by means of the knob 10 from its normal extreme position to its reverse extreme position. During the first half of the stroke of the operating shaft the cam slot 44 will cooperate with the upper cam follower 42 to move it downwardly, but will not cause any movement

of the other cam follower, whereas during the last half of the stroke of the operating shaft the cam slot 44 will cooperate with the lower follower to move it downwardly but will not cause any movement of the upper follower. The downward movement of the upper follower will act through the associated contact operating member to move the associated movable contact fingers from their closed to their open positions while the downward movement of the lower follower will act through the associated contact operating member to move the associated movable fingers from their open to their closed positions, thus providing sequential operation of the two sets of contacts. While the shaft is moving from one extreme position to the other, the steel ball 12 will be depressed for the first half of the stroke, but during the last half of the stroke the spring 18 will force the ball upwardly to exert a torque on the shaft which causes it to complete its stroke with a snap action.

The operation of the controller when the shaft occupies its reverse position, and it is desired to return it to its normal position is just the reverse of that just described and will be obvious from the foregoing without further detailed description.

Referring now to Figs. 7 to 11, inclusive, the modified form of circuit controller here illustrated comprises a supporting bracket 60 which corresponds to the supporting bracket 1 of the previously described circuit controller, and which is provided with a vertical leg 60a and a horizontal leg 60b. The vertical leg 60a is secured to the rear face of the control panel 2 by means of screws 4, and is provided at its upper end with an offset portion 60c containing a threaded opening 60d which receives a bushing 61. The operating shaft 6 of the controller is journaled in the bushing 61 and in an aligned bearing opening 62a formed in a support 62 secured by means of screws 63 to the rear face of the offset portion 60c of the bracket 60, and has pinned thereto between the offset portion and the bearing bracket a gear wheel 64 which meshes with a gear segment 65 pinned to a jackshaft 66. The jackshaft 66, in turn, is journaled in aligned bearing openings formed in the leg 60a and in a pedestal 67 secured to the leg 60b of the bracket 60, and carries a combination cam 68 which takes the place of the two cams 11 and 45 of the circuit controller illustrated in the preceding views. The combination cam 68 is formed with a cam slot provided with end portions 68a and 68b connected by an intermediate connecting portion 68c. The end portions and the intermediate connecting portions are all concentric with the axis of the shaft, but the intermediate portion has a longer radius of curvature than the two end portions. The cam is also provided with a projection 69. The cam slot cooperates with cam followers 42 comprising part of contact shifters for operating the contacts of the controller, while the projection 69 cooperates with a steel ball 70 forming part of detent means for causing the operating shaft 6 to complete its stroke with a snap action. The contacts of the controller are similar in all respects to those of the controller shown in Figs. 1 to 6, inclusive, but the contact shifter for the group of normally open contacts differs from that shown in Figs. 1 to 6 in that the cam support 43 extends upwardly instead of downwardly. The detent means is likewise similar to that shown in Figs. 1 to 6 except for the fact that the spring 18 bears directly against the ball 70. The operating

shaft 6 extends outwardly through a clearance hole in the panel 2, and is provided at its outer end with an operating knob 10.

The circuit controller also includes latch means comprising the spring 20. As here shown, however, this spring is secured to the offset portion 60c of the bracket 60, and extends transversely of the controller directly in back of the panel 2 and cooperates at its offset portion 20b with the push button 22. The pin 24 carried by the spring 12 is made slightly longer than in Figs. 1 to 6, and extends through a clearance hole in the panel 2 and cooperates with holes 10c and 10d formed in the control knob in such position that the hole 10c will receive the pin when the knob is rotated to its one extreme position and the hole 10d will receive the pin when the knob is rotated to its other extreme position. It will be obvious, of course, that the pin 24 can be withdrawn from the holes 10c and 10d by operating the push button 22.

The parts are so proportioned that the operating knob is free to rotate through an angle of 180°, and that rotation of the knob through this angle will act through the gear 64 and gear segment 65 to rotate the cam 68 through an angle of 80°. The parts are further so proportioned that when either cam follower is in the end portion 68a or 68b of the cam slot, the other pin will be in the intermediate connecting portion 68c, and that the difference in the radius of curvature between the end portions and the central connecting portion is sufficient to cause the necessary vertical movement of the contact shifters in response to rotation of the operating shaft from one extreme position to the other to open the contacts of the one group and close the contacts of the other group. It follows, therefore, that with the controller constructed as shown in Figs. 7 to 11, inclusive, operation of the control knob 10 between its two extreme positions will cause sequential operation of the contacts of the two groups in a manner equivalent to that obtained with the construction shown in Figs. 1 to 6, inclusive.

It should be noted that in both forms of controllers the means for latching the controller in its two extreme positions may not be required for certain applications, and when this is the case this latching means may be omitted.

It should also be noted that in both forms of controllers the metal stops 39 are so designed that they will break apart the contacts if they fuse together due to current arcs.

Although we have herein shown and described only two forms of circuit controllers embodying our invention, it is understood that various changes and modifications may be made therein within the scope of the appended claims without departing from the spirit and scope of our invention.

Having thus described our invention, what we claim is:

1. A circuit controller comprising a supporting bracket, a stack of contacts secured to said bracket, each said contact comprising a fixed and a movable contact finger clamped at one end in parallel spaced relation between insulating blocks, a contact shifter comprising a flat spring clamped at one end in said stack and provided at the other end with an insulating contact operating member formed with slots which receive the free ends of said movable contact fingers, an operating shaft journaled in said bracket, and cam means connecting said shaft with said contact shifter and

effective to positively move said shifter in opposite directions between two extreme positions to operate said contacts in response to operation of said shaft between its two extreme positions.

5. 2. A circuit controller comprising a supporting bracket, a stack of contacts secured to said bracket, each said contact comprising a fixed and a movable contact finger clamped in superposed spaced parallel relation between insulating blocks, a contact shifter associated with said contacts and comprising a flat spring clamped at one end in said stack and provided at the other end with a return bend which increases the stiffness of the spring in the horizontal plane while permitting said spring to flex in the vertical plane, an insulating contact operating member secured to said return bend and provided with slots which receive the free ends of said contact fingers to operatively connect the fingers with said contact operating member, an operating shaft journaled in said bracket, and cam means operatively connecting said shaft with said contact shifter and effective to positively move said shifter in opposite directions between two extreme positions in response to rotation of said shaft between its two extreme positions.
10. 3. A circuit controller comprising a supporting bracket, a stack of contacts secured to said bracket, said contacts being divided into two groups and each said contact comprising a fixed and a movable contact finger clamped in superposed parallel spaced relation between insulating blocks; a contact shifter associated with each group of contacts and comprising a flat spring clamped at one end in said stack and extending parallel to the contact fingers of the associated contacts and an insulating contact operating member secured to the free end of each said spring and each provided with slots which receive the free ends of the movable contact fingers of the contacts of the associated groups; an operating shaft journaled in said bracket; and cam means operatively connecting each said contact shifter with said shaft and effective to sequentially move said contact shifters between two extreme positions to sequentially operate the contacts of said two groups in response to operation of said shaft between its two extreme positions.
15. 4. A circuit controller comprising a supporting bracket, a stack of contacts secured to said bracket, each said contact comprising a fixed and a movable contact finger clamped at one end in parallel spaced relation between insulating blocks, a contact shifter comprising a flat spring clamped at one end in said stack and provided at the other end with an insulating contact operating member formed with slots which receive the free ends of said movable contact fingers, an operating shaft journaled in said bracket, cam means connecting said shaft with said contact shifter and effective to positively move said shifter in opposite directions between two extreme positions to operate said contacts in response to operation of said shaft between its two extreme positions, and detent means connected with said operating shaft and effective to cause said shaft to complete its stroke to either extreme position with a snap action.
20. 5. A circuit controller comprising a supporting bracket, a stack of contacts secured to said bracket, each said contact comprising a fixed and a movable contact finger clamped at one end in parallel spaced relation between insulating blocks, a contact shifter comprising a flat spring clamped at one end in said stack and provided at the

other end with an insulating contact operating member formed with slots which receive the free end of said movable contact fingers, an operating shaft journaled in said bracket, cam means connecting said shaft with said contact shifter and effective to positively move said shifter in opposite directions between two extreme positions to operate said contacts in response to operation of said shaft between its two extreme positions, detent means connected with said operating shaft and effective to cause said shaft to complete its stroke to either extreme position with a snap action, and latch means connected with said shaft for latching said shaft in its extreme positions.

6. A circuit controller comprising a supporting bracket, a stack of contacts secured to said bracket, said contacts being divided into two groups, a contact shifter operatively associated with each group of contacts and each provided with a cam follower, an operating shaft journaled in said bracket, a cam secured to said shaft and provided with a cam slot a part of which is concentric with respect to the axis of said shaft and the remainder of which is eccentric with respect to the axis of said shaft, said cam followers extending into said slot at diametrically opposite points and the parts being so proportioned that when one follower is in the eccentric portion of the slot the other follower will be disposed in the concentric portion and vice versa.

7. A circuit controller comprising a supporting bracket, a stack of contacts secured to said bracket, said contacts being divided into two groups, a contact shifter operatively associated with each group of contacts and each provided with a cam follower, an operating shaft journaled in said bracket, a first cam secured to said shaft and provided with a cam slot a part of which is concentric with respect to the axis of said shaft and the remainder of which is eccentric with respect to the axis of said slot, said cam followers extending into said slot at diametrically opposite points and the parts being so proportioned that when one follower is in the eccentric portion of the slot the other follower will be disposed in the concentric portion and vice versa, a second cam secured to said shaft, said second cam being provided with curved shoulders and with an eccentric intermediate portion of varying radius, and spring pressed means engaging said second cam and cooperating with said shoulders to limit the extreme positions of the shaft and with said eccentric portion to urge the shaft to its extreme positions with a snap action.

8. A circuit controller comprising a supporting bracket, a stack of contacts secured to said bracket, said contacts being divided into two groups, a contact shifter associated with each group of contacts and each provided with a cam follower, an operating shaft journaled in said bracket, a first cam secured to said shaft and provided with a cam slot a part of which is concentric with respect to the axis of said shaft and the remainder of which is eccentric with respect

to the axis of said shaft, said cam followers extending into said slot at diametrically opposite points and the parts being so proportioned that when one follower is in the eccentric portion of the slot the other follower will be disposed in the concentric portion and vice versa, a second cam secured to said shaft, said second cam being provided with curved shoulders and with an eccentric intermediate portion of varying radius and 5 with a pair of spaced holes, spring pressed means engaging said second cam and cooperating with said shoulders to limit the extreme positions of the shaft and with said eccentric portion to urge said shaft to its extreme positions with a snap 10 action, and latch means comprising a spring carrying a pin adapted to enter one of the holes in said second cam in one extreme position of the shaft and another one of said holes in said cam in the other extreme position of said shaft.

15 9. A circuit controller comprising a supporting bracket, a stack of contacts secured to said bracket, said contacts being divided into two groups, a contact shifter operatively associated with each group of contacts and provided with a cam follower, an operating shaft journaled in said bracket, a cam operatively connected with said shaft and provided with a cam slot having two end portions and an intermediate connecting portion all concentric with respect to the axis 20 of rotation of the cam, said end portions having a different radius of curvature from said intermediate connecting portion and said cam followers being so disposed that when said shaft occupies its extreme positions one of said cam followers will be disposed in a corresponding end portion of said slot and the other follower will be disposed in the intermediate connecting portion and that as the one follower moves out of either end portion into the intermediate portion the other 25 follower will simultaneously enter the intermediate portion to provide sequential operation of said contacts.

30 40 10. A circuit controller comprising a supporting bracket, a stack of contacts secured to said bracket, each said contact comprising a fixed and a movable contact finger clamped at one end in parallel spaced relation between insulating blocks, a contact shifter comprising a flat spring mounted at one end in said stack and provided 45 at the other end with an insulating contact operating member formed with slots which receive the free ends of the movable contact fingers to 50 operatively connect the fingers with said contact shifter, an operating shaft journaled in said bracket, a jackshaft journaled in said bracket and connected with said operating shaft by gear means, a cam secured to said jackshaft, and a cam follower secured to said contact shifter and cooperating with said cam to positively move 55 said shifter in opposite directions between two extreme positions to operate said contacts in response to operation of said operating shaft between its two extreme positions.
